Specification for Design.

Patented Apr. 11, 1916.

Application filed January 19, 1916. Serial No. 73,079. Term of patent 3½ years.

To all whom it may concern:

Be it known that I, CHARLES E. JONES, a citizen of the United States, residing at Chicago, in the county of Cook and State of Illinois, have invented a new, original, and ornamental Design for an Arm for Electric-Fixture Brackets and Semi-Indirect Bowls, of which the following is a specification, reference being had to the accompanying drawing, forming part thereof.

The figure is a perspective view of an arm for electric fixture bracket and semi-indirect bowl, showing my new design.

I claim:

The ornamental design for an arm for electric fixture bracket and semi-indirect bowl, as shown.

CHARLES E. JONES.
